TAMPING BAR CLAMP

Oscar Tuerck, Portland, Oreg., assignor to Tuerck-Mackenzie Company, Portland, Oreg., a corporation of Oregon

Application November 30, 1938, Serial No. 243,195

11 Claims. (Cl. 25—37)

This invention relates to a tamping device, and, more specifically, to tamping apparatus used in machines for making concrete-pipe and the like.

In concrete-pipe machines, such for example, as the concrete pipe machine shown in United States Letters Patent No. 1,532,937, issued January 20, 1925, to which reference is made, it is necessary to have suitable means for tamping the concrete mixture as it is fed into the pipe mold. Such means, in concrete-pipe machines of the type referred to, customarily comprises one or more tamping bars clamped to a suitable reciprocating mechanism.

The clamp by which the tamping bar or bars are attached to the reciprocating mechanism must be so arranged and constructed that sufficient tamping force will be imparted to the tamping bars and still permit of gradual upward slippage of the tamping bars through the clamp as the material or concrete mixture rises within the mold. Furthermore, when one mold has been filled, and is replaced by an empty mold, the tamping bars must be released and returned to their original position in order to start the tamping operation again.

An object of this invention is to provide an improved tamping-bar clamp which will facilitate the releasing of the tamping-bars whenever this is desired, and similarly will facilitate the clamping of the bars again subsequent to such release.

Another object of this invention is to provide a clamp of this type with which the clamping force may be easily increased or decreased without interrupting the tamping operation and without necessitating any releasing or adjusting of the tamping-bars or associated parts.

A further object of this invention is to provide a tamping-bar clamp which can be adjusted for tamping-bars of different thickness, and can be adjusted so as to compensate for wear on the tamping bars or shoes associated therewith.

An additional object of this invention is to provide an adjustable clamp which will not work loose while the tamping machine is in operation and will not become less efficient due to ordinary wear of any of the parts.

A still further object is to provide a tamping-bar clamp designed to meet the above requirements which will, nevertheless, be simple in construction and inexpensive to manufacture. These and incidental objects are attained by making the clamping device with a cam lever and with an adjustable screw socket, and, furthermore, by constructing and mounting the members of

the clamping mechanism in the manner hereinafter described with reference to the accompanying drawings, wherein

Fig. 1 is an assembly view of a concrete-pipe-making machine, the tamping mechanism being shown in full line and the remainder of the machine in broken line;

Fig. 2 is a transverse section taken on line 2—2 of Fig. 1, but drawn on a larger scale;

Fig. 3 is a front elevation of my improved tamping-bar friction clamp;

Fig. 4 is a vertical medial section taken on line 4—4 of Fig. 3;

Fig. 5 is a detail plan view of my improved means for variably adjusting and for rapidly setting or releasing the frictional engagement of the clamp with the tamping bars;

Fig. 6 is a corresponding medial section taken on line 6—6 of Fig. 5;

Fig. 7 is a transverse section taken on line 7—7 of Fig. 6 and illustrating an important detail of construction; and

Fig. 8 is a plan view of the cam-operated thruster shown removed from the structure illustrated in Fig. 5.

In concrete-pipe-fabricating machines of the type illustrated in Fig. 1, the entire apparatus for tamping the moist concrete, as it is deposited in the space between the stationary core and rotating jacket of the pipe mold, is customarily carried on swinging brackets such as *a* and *b* mounted on the standard *c* of the machine frame, these brackets *a* and *b* being shown in full line in Fig. 1. A frame *d*, which is secured to the swinging brackets *a* and *b*, is provided with an integral boss *e* and with sleeve blocks *f* and *g* disposed above and below the boss. The boss *e* serves as a journal for the shaft *h* which is also supported by other bearings such as *i* mounted on the bracket *a*, and the shaft *h* is driven by an electric motor *j* through the media of suitable power transmitting means as for example the belt drive shown.

The usual eccentric wheel *k* is keyed to the forwardly extending end of the driven shaft *h*, and a connecting rod *l*, rotatably mounted at one end on a pin made fast in an eccentric position on the wheel *k* and at the other end on a stub shaft integral with the housing *m* of the tamping-bar clamp *n*, serves to convert and transmit the rotary motion of the wheel *k* to vertically reciprocating movement of the tamping-bar clamp *n* in the manner customary in concrete-pipe-making machines.

A pair of bars *o* and *p*, slidably disposed in the

- sleeve blocks *f* and *g* and adjustably secured thereto by set screws, serve as means for manually swinging the tamping mechanism horizontally to the desired position with respect to 5 the pipe mold. These bars carry guide blocks *g* and *r*, respectively, which provide guideways for the reciprocating tamping bars above and below the reciprocating clamp *n*. (See also Fig. 2.)
- 10 The number of tamping bars employed depends, of course, on the number of circular plies of metal reinforcing material placed in the bars. Since the commonly used sizes of pipe require only one such reinforcing element, my improved 15 friction clamp has been shown in the drawings and will be presently described as applied to the usual pair of tamping bars, these bars being designated *s* and *t*, it being understood that my improved clamp may be used with any number 20 of tamping bars, or with only a single tamping bar. The tamping bars, which are customarily made of hardwood and have metal shoes secured to their lower extremities, extend through the housing *10* of the friction clamp *n* (see Figs. 25 2 and 4).
- The clamp *n* is equipped with the usual friction shoes *v* and *w* and with the spacer *x*, substantially as shown in Fig. 4. These friction elements are preferably provided with leather covering on the surfaces engaging the tamping bars and are loosely disposed in the box-like housing *10* of the clamp *n*. Pressure brought to bear 30 on a leaf spring *y*, disposed in the housing *10* and operative on the friction shoe *v*, forces the shoes *v* and *w* and the spacer *x* into frictional engagement with the interposed tamping bars. The housing *10* of the clamp *n* is provided with a central integral boss *10'* which is internally threaded to receive the externally threaded portion 35 *11* of an adjusting screw generally designated *12* and shown in detail in Figs. 5 and 6.
- 40 The outwardly extending end portion of the adjusting screw *12* is bifurcated to form a yoke for the disk-like cam head *13* of a lever *14* which is mounted for arcuate movement on a pin *15* disposed in the bifurcated end of the yoke so as to be eccentric with respect to the substantially circular cam portion *13* of the lever *14* as seen in Fig. 6. A counterbalance *16*, of suitable proportions, is formed integrally with or firmly secured to the cam *13* and is disposed on the periphery thereof in such manner as to enhance the 45 tendency of the lever *14* to gravitate to the pressure-applying position shown in the several figures and, in addition, to partially counteract the weight of the outstanding lever *14* when the adjusting screw is rotated to positions such as those shown in broken outline in Fig. 3. This latter function of the counterbalance *16* will be more 50 fully explained later. The cam *13* is provided with a peripheral groove *17* extending almost half way around the cam from a point adjacent the counter-balance *16* to a shoulder *17'* (Fig. 6) which incidentally functions as a stop to limit the 55 arcuate downward movement of the lever arm *14*. The body of the adjusting screw *12* is formed with a concentric bore in which is reciprocably disposed a substantially cylindrical thruster or cam follower *18* (shown isolated in Fig. 8), one 60 end of which is bifurcated to receive a roller *19*. The roller *19* is mounted on a fixed pin *20* and adapted to traverse the cam groove *17* and affords rolling contact between the cam and the thruster. A semi-spherical or other projection *21* formed 65 on the opposite end of the thruster *18* registers

with a central hole provided in the leaf spring *y* and prevents the latter from shifting when the pressure thereon is released by arcuate upward movement of the cam lever *14*.

It will be apparent from Fig. 4 that arcuate 5 downward movement of the cam lever *14* will cause the thruster *18* to be moved inwardly within the body of the adjusting screw *12* and to compress the leaf spring *y* against the friction shoe *v*. The amount of pressure thus exerted 10 on the leaf spring will depend on the position of the adjusting screw *12* in the boss *10'*. But the position of the adjusting screw *12* may readily be varied by screwing it toward or away from the leaf spring *y* using the lever *14* as an aid in 15 rotating the screw. This action is illustrated by the broken lines in Fig. 3.

While the external threads of the adjusting screw *12* are made a reasonably tight fit in the internal threads of the boss *10'*, frequent adjustment of the screw *12* would eventually wear the threads somewhat and result in a slack fit. In order to maintain the proper fit of the adjusting screw *12* in the boss *10'* and so prolong the efficient working life of the clamping mechanism I 20 provide the threaded portion of the adjusting screw *12* with a plurality of longitudinal slots *22*, preferably three, as shown in Fig. 7, these slots *22* divide the threaded portion *11* of the adjusting screw into three similar sections which are 25 made with a tendency to expand radially. Thus a proper fit of the slotted threaded portion is assured in spite of any gradual wear of the screw threads.

The operation of my clamp may now be described with particular reference to Fig. 2. As the moist concrete materials accumulate in the pipe mold in the space between the stationary core *A* and the rotating jacket *B*, it is necessary to permit the tamping bars *s* and *t*, which are 40 being reciprocated by the motor-driven eccentric wheel *k* and mechanism heretofore described, gradually to be pushed upward in the friction clamp *n* at a rate approximately equal to the rate of rise of the materials in the mold. 45

When the mold has been completely filled the motor actuating the tamping bars is shut off, the core *A* is raised above the jacket *B*, the jacket *B* containing the molded pipe is moved away, and replaced by an empty jacket, whereupon the 50 core *A* is dropped down again into place, the reinforcement placed in the mold, and the concrete or moist mixture is again fed into the mold. The tamping bars are then quickly released permitting them to drop down into the mold, and 55 are again clamped, while the motor reciprocating the clamping bars starts operating. It is obvious that, with the use of my clamp, all that it is necessary for the operator to do, in order to drop the tamping bars into place and secure them, is to 60 move the lever handle *14* into the position shown by the broken line in Fig. 6, which immediately permits the tamping bars to drop to the bottom of the mold, and then return the lever handle *14* to the normal clamping position. This requires 65 considerably less effort and time than is required, for example, with the ordinary screw clamp such as that illustrated in United States Patent No. 1,523,937, previously referred to. Furthermore, when my clamp is released and again clamped, 70 during the changing of the mold, there is no disturbance of the adjustment of the clamp, and consequently the operator is assured of obtaining the same clamping pressure on the tamping bars. This is very important, since too much or too little 75

clamping pressure would greatly influence the tamping force exerted by the machine.

It is a well-known fact, however, that it is difficult to obtain exact uniformity in the proportions and moisture content of the mixture fed into the pipe mold, and consequently it is necessary to make occasional adjustments in the tamping force in order to maintain the density of the tamped material in the pipe as constant as possible. The ear of the experienced operator can detect slight changes in density from variations in the sound made by the impact of the tamping bars with the material. The operator then tightens or loosens the clamp slightly in order to obtain greater or less tamping force. With my clamp this is done very easily merely by pushing the lever slightly either clockwise or counter clockwise, as the case may be, for example into one of the positions illustrated by the broken lines in Fig. 3. It is not even necessary to stop the action of the tamping bars in order to obtain this adjustment in the tamping force exerted. The constant, reasonably tight fit of the cooperating screw threads on the screw 12 and in the boss 10', together with the counter-balancing effect of the counter-weight 16, will sustain the screw and hand lever in such adjusted position, and, of course, the hand lever 14 can be actuated to release the tamping bars and re-clamp them, at the time of the changing of the mold just as easily as when the hand lever swings in a vertical plane.

It would, of course, be possible to make minor changes in the form and construction of the cam, hand lever, and thruster without departing from the principle of my invention. It is not my intention to limit my invention otherwise than as stated in the accompanying claims.

I claim:

1. In a tamping device of the character described, a tamping bar clamp including a housing, a spring within said housing, means for applying tension to said spring comprising, an adjusting screw extending into said housing, a concentric bore extending thru said screw, a thruster element slidable within said bore, the inner end of said thruster bearing against said spring, a cam lever pivotally mounted in the outer end of said screw and bearing against the outer end of said thruster, whereby, when said lever is moved into one position, said thruster will be caused to compress said spring.

2. In a clamp of the character described, a housing, a spring within said housing, means for applying tension to said spring comprising an adjusting screw extending into said housing, an aperture extending longitudinally thru said screw, a thruster element slidable within said aperture, the inner end of said thruster bearing against said spring, a cam lever pivotally mounted in the outer end of said screw and bearing against the outer end of said thruster, whereby, when said lever is moved into one position, said thruster will be caused to compress said spring, a counter-balance on said cam lever, said counter-balance adapted to reduce the tendency of said lever to cause said screw to turn when said lever is moved out of a vertical plane.

3. A tamping bar clamp comprising a housing, friction shoes supported by said housing, a spring within said housing adapted to apply tension to said friction shoes, an adjusting screw extending into said housing, a concentric bore extending thru said screw, a thruster element slidable within said bore, the inner end of said thruster

bearing against said spring, a cam lever pivotally mounted in the outer end of said screw and bearing against the outer end of said thruster, whereby, when said lever is moved into one position, said thruster will be caused to compress said spring, the threaded portion of said screw having a plurality of longitudinal slots to permit the radial expansion of said screw and thereby maintain a tight fit of said screw. 5

4. In a tamping device of the character described, including a pair of tamping bars, a tamping bar clamp including a housing, said tamping bars extending thru said housing, a spacer in said housing between said tamping bars, friction producing means within said housing, 10 means for applying tension to said friction producing means comprising an adjusting screw extending into said housing, an aperture extending longitudinally thru said screw, a thruster element slidable within said aperture, the inner end of said thruster bearing against said friction producing means, a cam lever pivotally mounted in the outer end of said screw and bearing against the outer end of said thruster, whereby, when said lever is moved into one position, said thruster will be caused to press against said friction producing means. 20

5. The combination described by claim 4 including a counter-balance on said cam lever, said counter-balance adapted to reduce the tendency of said lever to cause said screw to turn when said lever is moved out of a vertical plane. 30

6. The combination described by claim 4 with the threaded portion of said screw having a plurality of longitudinal slots to permit the radial expansion of said screw and thereby maintain a tight fit of said screw. 35

7. In a clamp of the character described, a housing, friction producing means within said housing, a thruster element extending thru one wall of said housing, the inner end of said thruster bearing against said friction producing means, a cam lever located outside of said housing and bearing against the outer end of said thruster, whereby, when said lever is moved into one position, said thruster will be caused to press against said friction producing means, a counter-balance on said cam lever adapted to maintain said cam in pressure applying position. 45

8. In a tamping device of the character described, a housing, friction shoes supported by said housing, a spring within said housing adapted to apply tension to said friction shoes, an adjusting screw extending into said housing, an aperture extending longitudinally thru said screw, 50 a thruster element slidable within said aperture, the inner end of said thruster bearing against said spring, cam means associated with the outer end of said adjusting screw and adapted to force said thruster inwardly, means for retaining said cam means in pressure applying position. 55

9. The combination described by claim 8 with the threaded portion of said screw having a plurality of longitudinal slots to permit the radial expansion of said screw and thereby maintain 60 a tight fit of said screw.

10. In a clamp of the character described, a housing, an adjusting screw extending into said housing, an aperture extending longitudinally thru said screw, a thruster element slidable within 70 said aperture, cam means associated with the outer end of said adjusting screw and adapted to force said thruster inwardly, a hand lever attached to said cam means, the threaded portion of said screw having a plurality of longitudu- 75

dinal slots to permit the radial expansion of said screw and thereby maintain a tight fit of said screw, a counter-balance on said cam lever, said counter-balance adapted to reduce the tendency of said lever to cause said screw to turn when said lever is moved out of a vertical plane.

11. In a tamping device of the character described, including a pair of tamping bars, a housing, said tamping bars extending thru said housing, a spacer in said housing between said tamping bars, friction shoes supported by said housing, means for adjusting the frictional engagement

of said shoes with said tamping bars, said means including a slidably mounted thruster element extending thru one wall of said housing and slidably mounted for movement in a direction substantially perpendicular to the direction of movement of said tamping bars, manually operated means for sliding said thruster inwardly in said housing, and means for adjusting the location of said manually operated means with respect to said housing.

OSCAR TUERCK. 10
